UNITED STATES PATENT OFFICE.

ARTHUR J. MOXHAM, OF JOHNSTOWN, PENNSYLVANIA.

RAILROAD-CROSSING.

SPECIFICATION forming part of Letters Patent No. 477,681, dated June 28, 1892.

Application filed September 22, 1891. Serial No. 408,497. (No model.)

To all whom it may concern:

Be it known that I, ARTHUR J. MOXHAM, of Johnstown, in the county of Cambria and State of Pennsylvania, have invented a new and useful Railroad-Crossing, which invention is fully set forth and illustrated in the following specification and accompanying drawings.

The objects of this invention are to provide a strong, safe, and durable crossing for street-cars over or across steam-railroad tracks which can be put in place without disturbing the latter track, and also to provide a strong and efficient guard for wheels passing over the steam-railroad track.

The invention will first be described in detail, and then particularly set forth in the claims.

In the accompanying drawings, Figure 1 is a general view in plan of the crossing. Fig. 2 shows in detail enlarged, one of the corners of the crossing at the right-hand side of Fig. 1. Fig. 3 is a vertical section taken through Fig. 2 at the line Y Y. Fig. 4 is a vertical section taken through Fig. 2 at the line X X. Fig. 5 is an enlarged view in plan, partly in section, of certain details hereinafter described. Fig. 6 is a vertical section taken through Fig. 5 at the line Z Z.

In said figures the several parts are respectively indicated by reference-letters, as follows:

The crossing consists of two outer portions A A and the center portion B. In each of said outer portions the letter *a* indicates the rails of the street-car track, seated upon chairs *c*, secured to the cross-ties *T*. Said rails are connected to an L-shaped bar *E* (laid parallel to the through-rails *D*) either by means of the angle splice-bars *e*, as shown at the right-hand side of Fig. 1, or by being directly welded to said L-bar, as shown at the point *w* at the left-hand side of said figure. In the latter case of course splice-bars can be dispensed with.

The guard portions *g* of the rails *a* are planed or otherwise cut away to a level with the head portion *j* to the points *h*, in order that no obstruction may be offered to the passage of snow-plows, which are sometimes attached to locomotives passing over the through-rails *D* and overhang said rails on either side.

The letters C C indicate chocks between the L-bars *E* and the rails *D*, which fit into the concavities in the sides of said rails, as shown in detail in Fig. 3. Said chocks are preferably located directly opposite the crossing-rails *a a*, but should said rails come opposite to a joint or splice-bar on the rails *D* the chocks should then be placed as near to this point as possible. Said chocks may be attached to the bars *E* by being directly welded thereto, as shown at *w'* at the left-hand side of Fig. 1, or they may be attached by means of the bolts *i*, as shown at the right-hand side of said figure, in which latter case said bolts pass through the angle splice-bars *e* when said splice-bars are used to connect the rails *a* to the bar *E*.

Referring now to the center portion of the crossing, (marked B,) said portion consists of two L-shaped bars *H H'*, parallel with the through-rails *D* between the crossing-rails *F F* and curved beyond said crossing-rails to a common junction at the points *J w*. At the point *J* the ends of said bars are shown as united and reinforced by means of the splice-bars *s*; but at the point *w* the other ends of said L-bars are shown as welded together. It is obvious that either the welded or the splice-bar connection could be used at both of said points. The ends of the L-bars, though preferably thus united, may be, if desired, entirely disconnected.

The heads of the crossing-rails *F F* abut the L-bars *H H'*, and said rails may be connected thereto either by means of splice-bars *e'*, as shown at the right-hand side of Fig. 1, or by being directly welded thereto, as shown at the points *w* at the left-hand side of said figure.

At the points marked C', Figs. 1, 2, and 3, between the through-rail *D* and L-bar *H*, are provided chocks, which may be connected to said L-bar either by means of bolts *i'* or by welding, both methods of connection being illustrated in Fig. 1, the letter *w* indicating the welded connection. On the opposite side, between the through-rail *D* and L-bar *H'*, removable chocks *W* are provided. If the chocks used on both sides were of the form of the chocks C', it would be impossible to place the center portion B in position without either removing the rails *D* or sliding the chocks in

- from the ends. It would, however, be difficult to slide such chocks into place, and if a joint existed in the rail D it would be impossible to slide the chocks past said joint.
- 5 This difficulty is overcome by the use of the removable chocks W, Figs. 1, 5, and 6, which are entered into the curved portion of the guard-piece H H' and at the ends, where easily accessible. By referring to Fig. 5 it will be seen that the chocks W are provided with recesses n to permit access to the bolts and nuts d, which bolts pass through slots o and secure said chocks to the web of the L-bar H'. It is obvious, however, that said chocks, instead of being made solid, as shown, and provided with recesses, could be made hollow or of skeleton form, as shown in my pending application, Serial No. 373,662, filed December 5, 1890.
- 10 It will be observed that the chocks W are not bolted to the main rails D, but only to the L-bar H'. By this construction the inner part B of the crossing can be laid between the through-rails D, pushed into place with the attached chocks C' bearing against the web of one of said through-rails, and the removable chocks W then slipped in from either end and attached to the guard-piece H H' at an accessible point.
- 15 30 The purpose of the guard-piece H H' is as follows: In practice there is considerable play in the trucks of steam-railroad cars passing over the rails D and consequent oscillation of the wheels from one side to the other. The bent ends of said guard-piece offer to an approaching train something to guide its wheels into the groove between the through-rails D and the L-bars H H', forming the guard-piece.
- 20 In railroad-crossings heretofore it has been proposed to use two rails having their ends bent to act as a guard; but such rails so bent depend upon spikes to hold them in place. By uniting into one piece both of the bars forming the guard-piece, as herein described,
- 25 35 great constructive strength is secured and the whole interior portion B of the crossing takes the impact of an approaching train instead of a portion thereof. This is an important advantage, for it has been found extremely difficult to keep independent guard-pieces in order.
- 40 45 By the construction herein described the whole crossing can be made out of rolled or forged steel or other metal and can be put in a steam-railroad track without the least disturbance of the latter.
- 50 55 The rails shown as forming the street-railroad track are well known to the trade as "girder guard-rails;" but, if desired, any other suitable form of rail may be substituted therefor.
- 60 I do not herein broadly claim a guard-piece composed of rails united at their ends, nor do I claim the removable chocks W *per se*, as such features are claimed in my pending application above mentioned; but,

Having thus fully described my said invention, I claim—

1. In a railroad-crossing, guard rails or bars between the through-rails, curved and welded together at their ends. 70
2. In a railroad-crossing, L-shaped guard-pieces between the through-rails, each having its ends curved and one of its sides horizontal and flush with the upper surface of said through-rails. 75
3. In a railroad-crossing, L-shaped bars between the through-rails, curved and united at their ends into a guard-piece. 80
4. In a railroad-crossing, L-shaped bars between the through-rails, curved and united at the ends by welding into a guard-piece complete for either direction. 85
5. In a railroad-crossing, in combination with two crossing-rails between the through-rails, a guard-piece composed of L-shaped bars curved and united at their ends into a guard-piece complete for either direction. 90
6. In a railroad-crossing, in combination with through and crossing rails, a guard-piece composed of L-shaped bars curved at their ends into a guard-piece complete for either direction, said guard-piece being provided with chocks between it and the through-rails. 95
7. In a railroad-crossing, a guard-piece composed of L-shaped bars curved at their ends to form the same, in combination with a through-rail and a removable chock, as W, having one straight and one curved face and provided with a recess or recesses, for the purposes set forth. 100
8. In a railroad-crossing, a guard-piece provided with a chock or chocks between said guard-piece and the through-rail, welded to said guard-piece. 105
9. In a railroad-crossing, a guard-piece composed of L-shaped bars curved at their ends to form the same and provided with a chock or chocks between said guard-piece and the through-rail, welded to said guard-piece. 110
10. In a railroad-crossing, a guard-piece provided with chocks welded thereto and removable chocks, said chocks being located between said guard-piece and the through-rails. 115
11. In a railroad-crossing, a guard-piece composed of L-shaped bars curved at their ends to form the same and provided with chocks secured thereto and with removable chocks between said guard-piece and the through-rails. 120
12. In a railroad-crossing, an L-shaped bar, as E, located outside of and parallel to the through-rails and having its upper surface flush with the upper surface of said through-rails. 125
13. In a railroad-crossing, the combination of an L-shaped bar, as E, and a chock or chocks between said bar and the through-rail, welded to said bar. 130
14. In a railroad-crossing, in combination with two crossing-rails, an L-shaped bar, as E, located outside of and parallel to the

through-rail and having its upper surface flush with the upper surface of said through-rail.

15. In a railroad-crossing, an L-shaped bar, as E, connecting the crossing-rails and welded to one or both of said rails.

16. In a railroad-crossing, the combination of a through-rail, an L-shaped bar, as E, having its upper surface flush with the upper surface of said through-rail, a crossing-rail, and a chock between said bar and through-rail.

17. In a railroad-crossing, the combination of an L-shaped bar, as E, a crossing-rail welded to said bar, a through-rail, and a chock between said bar and through-rail, for the purposes set forth.

18. In a railroad-crossing, the combination of a through-rail, a crossing-rail, an L-shaped bar, as E, and a chock or chocks between said bar and through-rail, welded to said bar, for the purposes set forth.

19. In a railroad-crossing, the combination of an L-shaped bar, as E, a through-rail, a crossing-rail, and a chock or chocks between said bar and through-rail, said crossing-rail and said chocks being welded to said bar.

20. In a railroad-crossing, the combination of the through and crossing rails, of L-shaped bars, as E, a curved guard-piece, and chocks between said guard-piece and the through-rails.

21. In a railroad-crossing, the combination of the through and crossing rails, L-shaped bars, as E, a curved guard-piece, chocks welded to

said guard-piece, and removable chocks, as W, 35 said chocks being located between said guard-piece and the through-rails.

22. In a railroad-crossing, the combination, with the through and crossing rails, of L-shaped bars, as E, a curved guard-piece, 40 chocks between said bars and the through-rails, and chocks between said guard-piece and the through-rails.

23. In a railroad-crossing, the combination of through and crossing rails, L-shaped bars, 45 as E, chocks between said bars and the through-rails, welded to said bars, a curved guard-piece, and chocks between said guard-piece and the through-rails, welded to said guard-piece.

24. In a railroad-crossing, the combination, with the through and crossing rails, of L-shaped bars, as E, a curved guard-piece, 50 chocks between said bars and the through-rails, and fixed and removable chocks between said guard-piece and the through-rails.

25. In a railroad-crossing, the combination of through and crossing rails, L-shaped bars, as E, chocks between said bars and the through-rails, welded to said bars, a curved 60 guard-piece, chocks between said guard-piece and one through-rail, welded to said guard-piece, and removable chocks between said guard-piece and the other through-rail.
